[57] CLAIM

The ornamental design for a death care merchandise display unit, as shown and described.

DESCRIPTION

FIG. 1 is a perspective view of a death care merchandise display unit from the front, side, and top, the perspective view from the opposite side being a mirror image thereof; and,

FIG. 2 is a side view of FIG. 1.

The broken lines showing form no part of the claimed design.

The surfaces or portions of the article not shown in the drawing or described in the specification form no part of the claimed design.

1 Claim, 2 Drawing Sheets
